CHARCOAL IGNITER FOR BARBECUES

William Bruce Delamater, 9114 Valley View,
Whittier, Calif. 90603

Filed Jan. 4, 1972, Ser. No. 215,449

Term of patent 14 years

Int. Cl. D26—99

U.S. Cl. D48—27 C

FIG. 1.

FIG. 2.

FIG. 3.

FIG. 1 is a top perspective view looking from the handle and toward the head of a charcoal igniter for barbeques, showing my new design;

FIG. 2 is a top perspective view, looking from the head toward the handle thereof; and,

FIG. 3 is a bottom perspective view looking from the handle toward the head thereof.

The undisclosed side of the head is flat and unornamented.

I claim:

The ornamental design for a charcoal igniter for barbeques, substantially as shown and described.
